CLAIM

The ornamental design for an ice cooler bag, as shown and described.

DESCRIPTION

FIG. 1 is a front view of an ice cooler bag showing the claimed design;

FIG. 2 is a rear view thereof;

FIG. 3 is a left side view thereof;

FIG. 4 is a right side view thereof;

FIG. 5 is a top view thereof;

FIG. 6 is a top front perspective view thereof; and,

FIG. 7 is another top front perspective view of the ice cooler bag with a belt.

A bottom view of the ice cooler bag is flat and unornamented.

The broken lines in the figures show portions of the ice cooler bag that form no part of the claimed design.
